UNITED STATES PATENT OFFICE.

RANKIN GARFIELD FOX, OF SEATTLE, WASHINGTON, ASSIGNOR TO BLACK MANUFACTURING COMPANY, OF SEATTLE, WASHINGTON.

SAFETY-POCKET.

1,201,713.

Specification of Letters Patent.

Patented Oct. 17, 1916.

Application filed March 3, 1913. Serial No. 751,850.

To all whom it may concern:

Be it known that I, RANKIN GARFIELD Fox, a citizen of the United States, residing at Seattle, in the county of King and State 5 of Washington, have invented certain new and useful Improvements in Safety-Pockets; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to wearing apparel, more particularly to overalls, and has for its object to provide the garment with a pocket so formed as to afford safety against its contents accidentally dropping out of 20 the pocket, the formation being effected by a simplicity of construction involving the minimum expenditure of time, labor and material while at the same time adding to the security or safety and convenience afforded by the pocket.

25 To the accomplishment of the foregoing and such other objects as may hereinafter appear the invention consists in the features hereinafter described and then sought 30 to be clearly defined by the claims, reference being had to the accompanying drawing forming a part hereof, and in which:

Figure 1 is a front view of a portion of a pair of overalls having the invention applied, and Fig. 2 a similar view with a portion of the pocket broken away and a part turned or folded the better to illustrate the interior of the pocket.

In the drawing the numeral 1 designates 40 the upper or apron portion of a pair of overalls having the patch portion 2 applied thereto to constitute the pocket. This patch has a top edge inclined upwardly from *a* to *b* and downwardly from *b* to *c*, 45 and has a bottom edge inclining from *d* to *e* so that the bottom of the pocket will incline downwardly from next to the side of the apron toward its central portion for a purpose hereinafter appearing, the double 50 incline of the top edge serving not only for the easy insertion of the hand but also adding to the safety of the pocket as will later appear. The upper and lower edges and also the outer edge of the patch will be 55 folded and secured by a double row of

stitching 3, and the patch will be attached to the body of the apron by the same or a similar line of stitching along the outer and the lower edge and along the portion from *b* to *c* except where the latter is left open to form the mouth for a pencil pocket 8 formed by a line of stitching 4 through the apron and patch, while the inner edge of the patch is inserted in the seam 5 of the apron and secured by the stitching 6 of that seam. From the inner corner of the top edge of the patch a line of stitching 7 is passed through the patch and apron so as to incline downwardly toward the lower outer corner of the pocket, said line of 70 stitching lying under the mouth of the pocket and forming an inclined passageway at the mouth of the pocket so that articles inserted will pass toward the lower outer corner of the pocket and then by the inclined bottom directed toward the lower inner corner of the pocket so as to lie in the compartment below the downward and inwardly inclined line of stitching 7. This 75 will bring the articles into such position that 80 when the wearer of the garment leans forward or to one side the articles will find a lodgment in the space or compartment beneath and adjacent to the line of stitching 7 so that they cannot slide out of the pocket. Should the wearer lean in the other direction 85 the articles will be caught and held either by the line of stitching 7 or by the inclined stitched edge from *b* to the mouth of the pencil pocket and thus be prevented 90 from sliding out of the inclined passageway immediately under the open inclined mouth of the pocket.

By the simple specially designed top edge of the pocket together with its inclined bottom and the downwardly inclined line of stitching 7 extending from the inner top corner of the pocket so as to form the inclined passageway a pocket is formed which will most effectively prevent articles from 95 accidentally slipping out of the pocket. At the same time the easy insertion and withdrawal of articles from the pocket is provided for, and the certainty of the articles assuming a position of safety when inserted in the pocket is assured. Again, the features of safety and convenience at the minimum expenditure of time and labor in providing the same is made possible by the 100 special features of construction specified all 105 110

of which are important items in the manufacture of garments of this character.

It is obvious that some of the features described may be omitted and the advantages of the other features retained but the best results are obtainable when the several features are employed in their relation one to another specified.

Having described my invention and set forth its merits what I claim is:—

1. In a garment, a safety-pocket consisting of a "patch" secured thereto to form an open crosswise extending mouth at the top of the pocket and provided with inclined lines of stitching at both sides of the pocket-mouth extending from opposite corners of the open mouth, one line of said stitching extending under the open mouth and in conjunction with the other line of stitching forming an inclined passage-way extending downwardly from the mouth of the pocket.

2. In a garment, a safety-pocket consisting of a "patch" secured thereto to form an open mouth at the top of the pocket and provided with inclined lines of stitching at both sides of the pocket-mouth, one line of said stitching extending under the open mouth and in conjunction with the other line of stitching forming an inclined passage-way extending downwardly from the mouth of the pocket, the bottom line of the pocket inclining downwardly from one corner to the opposite corner under the line of stitching which extends under the mouth of the pocket.

In testimony whereof I affix my signature in presence of two witnesses.

RANKIN GARFIELD FOX.
